Patented Aug. 11, 1964

198,832

PAPER ROLL HOLDER

George Moy, Warren, Mich., assignor to Handy Things
Manufacturing Company, Ludington, Mich.

Filed Sept. 9, 1963, Ser. No. 76,516

Term of patent 14 years

(Cl. D4—3)

FIG. 1 is a front perspective view of a paper roll holder embodying my new design.

FIG. 2 is a rear perspective view.

FIG. 3 is a plan view.

FIG. 4 is an end view.

FIG. 5 is a sectional view on a line corresponding to line 5—5 of FIG. 3.

I claim:

The ornamental design for paper roll holder, as shown.
